UNITED STATES PATENT OFFICE.

WILLIAM J. LUCKS, OF COLUMBUS, OHIO.

VALVE-GRINDER.

1,396,861.

Specification of Letters Patent. Patented Nov. 15, 1921.

Application filed January 12, 1921. Serial No. 436,651.

To all whom it may concern:

Be it known that WILLIAM J. LUCKS, a citizen of the United States, residing at Columbus, in the county of Franklin and State of Ohio, has invented certain new and useful Improvements in Valve-Grinders, of which the following is a specification.

This invention relates broadly to valve grinders, and has for its primary object to 10 provide a valve grinder of improved and simplified construction and which may be employed in restricted spaces with convenience and facility, in order that the valve seats of an internal combustion engine may 15 be accurately and smoothly ground or finished and without requiring the removal of any but necessary parts thereof.

In the average forms of valve grinders the valve rotating stems thereof are usually 20 oscillated by means of rotary crank structures. It is found in practice that such structures are open to the objection that the same are quite cumbersome in construction and require considerable space in which 25 to effect their operation. This objection is quite a pertinent one, because of the fact that unless an engine is considerably dismantled, the operator of the grinder will be materially inconvenienced and hampered 30 in successfully operating the tool, and furthermore, such operation is both difficult and laborious.

The present invention aims to overcome these and other objections in valve grinders 35 by producing a tool which will be simple and easy to operate and one which will require but a minimum of space in which to effect its successful operation.

With these and other objects in view, as 40 will appear as the description proceeds, the invention accordingly consists in the novel features of construction, combinations of elements and arrangements of parts, herein-after fully described and pointed out in the 45 appended claim.

In the accompanying drawing, forming a part of this specification, and in which similar characters of reference denote like and corresponding parts throughout the several 50 views thereof:

Figure 1 is a vertical longitudinal sectional view taken through the improved valve grinder comprising the present invention, and

55 Fig. 2 is a horizontal sectional view taken along the line of 2-2 of Fig. 1.

Referring more particularly to the details of the invention, my improved valve grinder consists essentially of a spiral shaft 1, which in this instance is formed from a plurality 60 of twisted wires, in this instance, three in number. By this construction a shaft will be produced which will possess the requisite degree of rigidity and effectively capable of withstanding the stresses and pressures 65 to which the shaft will be placed when in actual use. Also, by this manner of constructing the shaft a double thread will be formed, which will permit of rapid rotary motion on the part of the shaft when the 70 grinder is operated. In order to support the shaft for oscillating movement use is made of a handle structure 2, which is formed to include a vertically extended bore or chamber 3, the latter being provided with 75 a closed upper end and with an open lower end, the said lower end being normally closed, however, by means of a metallic cap 4, which is adapted to be removable yet securely retained in conjunction with the 80 lower end of the handle structure 2. The cap 4 is provided with an opening 5 therein, which conforms exactly with the cross sectional configuration of the shaft 1, and by this construction it will be manifest that 85 when vertical reciprocatory motion is imparted to the handle structure, rotation or oscillation on the part of the shaft will be effected. Then, to impart the movement of the shaft to a valve disk, the lower ends of 90 certain of the wires constituting the shaft which are laterally bent to produce spaced fingers 6, which are adapted to the position within the usual openings 7, provided in a valve disk 8, this construction serving as 95 usual to permit of the forced rotation of the disk 8 upon its seat.

The upper end of the shaft 1 extends through the opening 5 provided in the cap 4 and projects into the bore or chamber 3 provided in the handle structure. The upper end of the shaft or stem is disposed in engagement with a metal cup 9, which is normally pressed downwardly and maintained in engagement with the upper end of the 105 shaft by means of a coiled spring 10, the latter, in turn, being confined between the upper end of the bore 3 and the said cup 9. By so engaging with the shaft 1 it will be manifest that the normal tendency or action 110 of the spring will be to force the shaft 1 downwardly, or conversely to elevate the

handle structure and to thus maintain the two constantly in a position best adapted for the application of manual pressures. If desired, the upper end of the stem or shaft 5 may be equipped with a collar 11, between which and the cap 4 a relatively small and weak spring 12 is situated. This supplemental spring serves to cushion or arrest the descent of the shaft 1, and to produce 10 a tool which may be smoothly and easily operated with an absence of quick, unnatural and jerky movements.

In view of the foregoing description, it would be apparent that the present invention 15 provides a valve grinder of improved design and construction which would be capable of operating in relatively restricted areas. It will be manifest that in operation the said handle structure will be manually 20 grasped and reciprocated vertically. Since the shaft 1 has its finger 6 in engagement with the valve disk 8, it would be apparent that such vertical movement on the part of the handle structure will result in rotating 25 the shaft 1 and consequently the disk 8, causing the latter to be rotated relatively to its seat so that the contacting surfaces of the valve structure may be smoothly ground. When the handle structure has been forced 30 downwardly to substantially its fullest extent, the same may be released so that it will automatically rise by reason of the influence of the main spring 10 and with a reversal of movement on the part of the 35 valve disk. The provision of the spring 10 thus operates to render the construction con-

venient to manipulate and to effect uniform and positive rotation of the part thereof. In other words, the handle structure will not be moved down upon the shaft 1 to the same position upon each given operation thus causing the said shaft to rotate the valve to different positions, a feature which is of prime importance in valve grinder construction, in that it eliminates the presence of all carbon deposit from the seat of the valve, and also effectively eliminates carbon ridges. Therefore, for uniformity and effectiveness in operation, the inclusion of the springs 10 and 12 furnishes the essence 50 of the present invention, and it is by the presence thereof that the present valve grinder is believed to constitute a distinct improvement of prior structures.

What is claimed is:

In a valve grinder, a spiral shaft, a handle structure having a bore formed therein arranged to slidably receive said shaft, means formed with the lower portion of said handle structure in coöperation with 60 said shaft to effect the rotation of the latter, when said handle structure is vertically reciprocated, a main spring positioned between the upper end of said shaft and said bore and normally serving to maintain the 65 shaft in an extended position, and a supplemental spring positioned between said first named means and coöoperative with said shaft for resiliently arresting outward movement on the part of the shaft. 70

In testimony whereof I affix my signature.

WILLIAM J. LUCKS.
